UNITED STATES PATENT OFFICE.

GEORGE HOLTZMANN, OF BALTIMORE, MARYLAND.

DESIGN FOR SCROLL-SAW FRAME.

Specification forming part of Design No. 7,206, dated February 24, 1874; application filed December 18, 1873.
[Term of Patent 7 years.]

To all whom it may concern:

Be it known that I, GEORGE HOLTZMANN, of Baltimore city, and State of Maryland, have invented a new and Improved Design for Scroll-Saw Frame; and I do hereby declare that the following is a full, clear, and exact description of the same, reference being had to the accompanying drawing forming a part of this specification, in which the figure is a side elevation.

The invention relates to a peculiar configuration by which a scroll-saw frame, or the part thereof which is visible, may be made to present to the eye a more agreeable aspect, as hereinafter described.

A represents the ordinary goose-neck frame, extending around from the point B in a curve to the point C, and in a straight line to the point D. From the point C I throw out downwardly the curved piece E, with the vertical

socket-piece e and upwardly curved pulley-piece F, while from the point D I cause the socket-piece G g almost exactly to correspond with the one E e, but reversed in position, and the upward piece H to be nearly corresponding to the piece F. This correspondence of conformation in correlative parts produces a pleasing effect upon the eye.

Having thus described my invention, what I claim as new is—

The design for a scroll-saw frame, as shown and described.

The above specification of my invention signed by me this 15th day of December, 1873.

GEO. HOLTZMANN.
